CLAIM

The ornamental design for a mug as shown and described.

DESCRIPTION

FIG. 1 is a perspective view of a mug showing my new design;

FIG. 2 is a front elevational view of the mug of FIG. 1;

FIG. 3 is a rear elevational view of the mug of FIG. 1;

FIG. 4 is a left side elevational view of the mug of FIG. 1;

FIG. 5 is a right side elevational view of the mug of FIG. 1;

FIG. 6 is a top plan view of the mug of FIG. 1; and,

FIG. 7 is a bottom plan view of the mug of FIG. 1.

The broken lines having consistent dash lengths (dash-dash-dash) illustrate portions of the mug that form no part of the claimed design.

The broken lines having inconsistent dash lengths (long dash-short dash-long dash) represent boundaries of the claimed design.
